UNITED STATES PATENT OFFICE.

PETER CAPARELLI, OF PHILADELPHIA, PENNSYLVANIA.

STOCKING.

Application filed December 14, 1926. Serial No. 154,795.

A very serious objection to circular knit stockings is that they have very bulky toes. This is due to the fact that heretofore the toe has been knit on the circular machine the same width as the ankle of the stocking. This not only produces an exceedingly and unnecessarily broad toe, but the sewed seam across the upper end of the toe cap is located at such an angle to the central longitudinal line of the foot that the foot must be stretched transversely in order to take out the pockers or wrinkles along said seam. The consequence is that the board on which the stocking is placed must have the toe very wide and the stretching is therefore effected transversely to the foot. This further widens a toe that is already excessively broad. The resultant product does not and cannot fit the foot of the wearer. If shoes or high toed slippers are worn, the toe of the stocking is wrinkled and bunched thereunder and is uncomfortable. If low slippers are worn, the loose wrinkled toe of the stocking is exposed and is unsightly. The result is that the cheaper tubular knit stocking has been practically supplanted by the more expensive flat knit full-fashioned hosiery.

The primary object of the present invention is to provide a stocking of the tubular knit variety in which the upper portion of the toe cap is knit narrower and shorter than the lower portion, and the seam connecting the top and toe cap more nearly approaches a parallel relation to the longitudinal median line of the foot. A narrow and longer board can be therefore employed, which by stretching the foot longitudinally, will take the wrinkles from the seam in question. The result is a stocking which has a relatively narrow toe with a toe cap, the upper portion of which is relatively short, thus resulting in a stocking foot produced on a circular machine that will smoothly fit the foot of the wearer.

45 In the accompanying drawings:

Figure 1 is a view in elevation of the preferred embodiment of the invention,

Figure 2 is a view diagrammatic in its character, and indicating the normal construction and form of the stocking in comparison to that of the present invention.

Figure 3 is a perspective view of the stocking foot as it appears on the foot of the wearer.

55 The stocking shown being produced on a circular machine may have the usual tubular

knit leg, a portion of which is illustrated at 3, and which may be modified in any well-known manner. The heel is suitably reinforced, as shown at 4 and 5. The foot comprises the top portion 6, preferably of light material and a reinforced sole 7, the juncture between the two forming a longitudinal line at 8. The toe cap 9, also of reinforced material, includes the usual longitudinal 60 gore 10, forming the juncture between the rows of knitted loops as is well understood. The portion of said cap below said gore 10 is designated 11 and the portion above the same is shown at 12. In the upper margin 65 of the portion 12 is the seam 13 formed by sewing the upper portion 12 of the toe cap to a marginal reinforcement 14 knitted to the front end of the light top 6.

In this construction, it will be noted that the gore 10 and the rear corner 15 of the toe cap formed by the junction of the rear ends of the sections 11 and 12 are above the upper edge 8 of the reinforced sole 7. It will also be noted that the seam 13 and the upper edge of the top section 12 of the toe forms with the line 10 an angle A that is much more acute than the angle B formed between the gore 10 and the rear edge of the lower section 11 of the toe cap. More than this, the foremost portion b of the upper edge of the toe cap section 12 extends well beyond the front end of the lower edge of the lower section 11. As a consequence the seam 14 is brought into more nearly parallel relation 75 to the longitudinal axis of the foot, which is defined generally by the line 8. Therefore a board inserted in the stocking and utilized to stretch the same, can be narrow and relatively long inasmuch as the longitudinal 80 stretching of the foot on the board will also longitudinally stretch the seam 14 and eliminate the wrinkles in said seam. This so far as I am aware has never been heretofore accomplished and perhaps may best be explained by the reference to Figure 2, where- 85 in full lines is shown a stocking of the form above described, with the above described seam, gore and lines all illustrated in full lines and given the same reference numerals as those above employed. The dotted lines indicate in outline the ordinary stocking in which the line 14a corresponds substantially to the usual line of the seam. With such a construction, it will be evident 90 that the longitudinal stretching of the foot will not stretch the seam 14a and said seam

can only be stretched by laterally stretching the toe. This is accomplished by inserting a wide board, resulting in a broad toe that does not fit the foot but wrinkles and bunches over the toes. As a consequence this type of foot has proven unpopular because of its unsightliness and uncomfortableness. The present improvement eliminates the objections and as this tubular knit product can 10 be cheaply produced, it marks a distinct advance in the art. Further than this the top of the toe cap is short and is hidden when low slippers are worn, while the portion of the light top 6 adjacent thereto lies smoothly and evenly on the foot.

From the foregoing, it is thought that the construction, operation and many advantages of the herein described invention will be apparent to those skilled in the art, with- 20 out further description, and it will be under- stood that various changes in the size, shape, proportion and minor details of construction may be resorted to without departing from the spirit or sacrificing any of the advan- 25 tages of the invention.

What I claim is:-

1. A tubular knit stocking having a reen- forced toe provided with a seam across its rear portion, the line of the said seam being 30 at an angle sufficiently acute to the central gore to cause it to stretch longitudinally upon longitudinal pull being exerted against the front end of the toe reenforcement.

2. A tubular knit stocking having a reen- forced toe cap, provided with a longitudinal 35

side gore extending from its rear end and terminating short of its front end and pro- 40 vided with divergent upper and lower rear edges extending from the rear end of said gore, a seam along the upper rear margin of the reenforcement extending at an angle to the gore that is more acute than the angle formed by the gore and the lower rear edge of the reenforcement.

3. A tubular knit stocking foot having a 45 reenforced sole portion and a top portion of lighter material than the sole portion, forming a line of junction that extends substan- tially longitudinally of the foot, and a reen- forced toe cap at the front end of said sole 50 and top, said toe cap being provided with a longitudinal side gore extending from its rear end and located on a line higher than the said line of junction between the sole reenforcement and top portion, and said toe 55 cap being provided with divergent upper and lower rear edges extending from the rear end of said gore, a seam along the upper rear margin of the reenforcement extending at an angle to the gore that is more acute than the 60 angle formed by the gore and the lower rear edge of the reenforcement.

4. A knitted stocking having a toe pocket 65 with a diagonal suture on each side, the dis- tance from the point of the toe pocket to the upper edge of the web forming the upper part of said toe pocket being less than the distance from the point of the toe pocket to the lower edge of the lower web.

PETER CAPARELI.
